Primary Examiner — Brandon M Rosati*Assistant Examiner* — Marissa J Cash(74) *Attorney, Agent, or Firm* — Gardner Groff Greenwald & Villanueva, PC(57) **CLAIM**

The ornamental design for a toy airplane, substantially as shown and described.

DESCRIPTION

FIG. 1 is a top perspective view of a toy airplane; FIG. 2 is a bottom perspective view of the toy airplane of FIG. 1; FIG. 3 is a front view of the toy airplane of FIG. 1; FIG. 4 is a rear view of the toy airplane of FIG. 1; FIG. 5 is a right side view of the toy airplane of FIG. 1; FIG. 6 is a left side view of the toy airplane of FIG. 1; FIG. 7 is a top view of the toy airplane of FIG. 1; and, FIG. 8 is a bottom view of the toy airplane of FIG. 1. In the drawings, the claimed design is defined by the shaded surfaces; broken lines immediately adjacent shaded surfaces represent boundaries of the claim and form no part thereof; all other broken lines depict unclaimed environmental subject matter and form no part of the claim.
